Primary Examiner — Cynthia R Underwood

(57) **CLAIM**

The ornamental design for an ipad leather case, as shown and described.

DESCRIPTION

FIG. 1 is a first perspective view of an ipad leather case showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the ipad leather case thereof; and,

FIG. 10 is a perspective view of another state of the ipad leather case thereof.

The broken lines shown in the drawings depict portions of the ipad leather case that form no part of the claimed design.
